UNITED STATES PATENT OFFICE.

JAMES H. MANN, JR., OF PINE BLUFF, ARKANSAS, ASSIGNOR TO TRANSIT VENDING MACHINE COMPANY, OF PINE BLUFF, ARKANSAS, A CORPORATION OF ARKANSAS.

COIN-CONTROLLED VENDING MACHINE.

1,408,112.

Specification of Letters Patent. Patented Feb. 28, 1922.

Application filed September 4, 1919. Serial No. 321,611.

To all whom it may concern:

Be it known that I, JAMES H. MANN, Jr., a citizen of the United States, residing at Pine Bluff, in the county of Jefferson and State of Arkansas, have invented certain new and useful Improvements in Coin-Controlled Vending Machines, of which the following is a specification, reference being had to the accompanying drawings.

10 This invention relates to the art of vending machines and more particularly to coin controlled type, in which the insertion of a proper coin into the machine is necessary, before it is possible for an actuator (which 15 forms an element of the machine) to operate the article delivering tray, to discharge the article to be vended.

Primarily, the invention aims to provide a vending machine of this kind, which is 20 simple, efficient and practical in construction, and which is a vast improvement over the vending machines set forth, claimed and illustrated in the prior Patents No. 1,217,616 and No. 1,278,186 issued to James H. Mann, 25 Jr., and is also an improvement over the construction shown, described and claimed in the pending application filed March 9, 1918, Serial No. 221,509.

Another object of the invention is to provide 30 a machine of this character involving in its construction the most essential features of the foregoing patents and the pending application, and at the same time eliminating other unessential features, hence resulting in a far superior and more practical machine for commercial purposes.

A further object of the invention resides 40 in featuring a free actuator, in lieu of the old style locking type of actuator, as disclosed in the former patents, and also to provide means on the actuator for closing the coin slots, thereby preventing a coin from being deposited in a non-operating machine.

45 A still further object of the invention consists in the provision of a coin operating mechanism to be operated by the actuator, for operating the article delivering tray, in combination with a plurality of means for locking said mechanism, thereby avoiding a coin being employed more than once by sus-

pending it on a thread when deposited into the chute.

The invention also resides in still further objects, first the simple assembling of the 55 various parts of the machine; a coin chute, which comprises upper and lower chutes and an intermediate chute (which may be termed a coin gauge to prevent all but the proper size of coin from entering the chute) 60 in combination with means for cooperating with said coin gauge adapted to operate to render the machine inoperative, particularly in case of a slug lodging in the coin gauge, and also to provide a machine, in which 65 the various parts can be easily and quickly assembled and removed.

While the design and construction at present illustrated and set forth is deemed preferable, it is obvious that as a result of a 70 reduction of the invention to a more practical form for commercial purposes, the invention may be susceptible to changes, and the right to these changes is claimed, provided they are comprehended within the 75 scope of what is claimed.

The invention comprises further features and combination of parts, as will be hereinafter set forth, shown in the drawings and claimed.

80 In the drawings:

Figure 1 is a perspective view of the vending machine.

Figure 2 is a perspective view of the vending machine, with the cover plate and glass 85 removed, and also the top, thereby clearly showing the article holding and delivering tray; the cover plate being shown above the outer casing, in readiness to be applied to the casing.

Figure 3 is a detail view of the upper portion of the outer casing, showing the top in a position ready to engage the outer casing.

Figure 4 is an enlarged detail perspective 95 view of the lever 117.

Figure 5 is a detail perspective view of the coin box.

Figure 6 is a perspective view of the inner casing of the vending machine, showing the vending machine mechanism detailed in perspective.

Figure 7 is a detail perspective view of the outer casing with the inner casing and its mechanism removed.

Figure 8 discloses detail views of the slug catching pawl and the actuator return pawl.

Figure 9 is a detail perspective view of the starting pawl.

Figure 10 is a detail perspective view of the tray actuating pawl.

10 Figure 11 is a detail perspective view of the dog 83.

Figure 12 is a detail perspective view of the cover plate 26^b of the coin gauge.

15 Figure 13 is a detail sectional view through a portion of the holding and delivering tray, showing the shaft 45 and the spring carried thereby.

Figure 14 is a detail perspective view of a portion of the holding and delivering tray

20 45, showing one of its ears 44 with its teeth 46 in engagement with a portion of the tray actuating pawl.

Figure 15 is a perspective view of the rear portion of the inner casing, showing the back reinforcing plate, it being apparent from the showing that the vending machine mechanism is carried in the inner casing.

Figure 16 is a detail perspective view of the actuator 67.

30 Figure 17 is a detail view in elevation of the coin gauge and the slug catching pawl, illustrating the actuator return pawl.

Figure 18 is a detail perspective view of the upper portion of the inner and outer casings, showing the lever 117, which holds the top of the outer casing in place.

Figure 19 is a detail perspective view of the coin actuated lever 50.

40 Figure 20 discloses detail perspective views of the base piece and the cover plate 26^a and 26^b of the coin gauge.

Figure 21 is a detail perspective view of the back reinforcing plate.

45 Figure 22 is a fragmentary view of the inner casing, partly in section and illustrating the coin actuated mechanism for tilting the delivering tray, showing the initial position of the parts.

50 Figure 23 is a view similar to Figure 22, but showing the coin actuated mechanism as having been operated, and the tray operating pawl having been moved one tooth in engagement with the dog 83 and illustrating the coin actuated lever as having been returned to a near normal position, and also showing the shoulder 66^a in position to cooperate with the lug 79.

Figure 24 is a view similar to Figures 22 and 23, showing the tray actuating pawl as having been moved another tooth, the coin actuated lever partially operated, say for instance substantially a near half movement.

60 Figure 25 is a view similar to Figures 22 to 24, showing the tray actuating pawl

moved another tooth and the coin actuated lever further moved, and the coin in a further position through the mechanism.

Figure 26 is a view similar to Figures 22 to 25 inclusive, showing the coin actuated lever 50 further moved, and the tray actuating pawl moved another tooth, and the coin having been discharged.

Figure 27 is a view similar to Figure 26, showing the tray actuating pawl further moved, almost to its limit, the coin actuated lever returned to its initial position, and the coin in the act of discharging.

Outer casing.

Referring more especially to the drawings, 1 designates the outer casing of the vending machine, which comprises the back piece 2 having its side flanges 3, the front piece 4, which is provided with inturned flanges forming guides 5, for the reception of the lateral flanges of the sides of the back piece, thereby enclosing the inner casing 7, which carries the operating mechanism of the vending machine. The outer casing has a top 8, which has overlying flanges 9 on three of its edges, which overlies the front piece and the sides of the back piece.

Inner casing.

The inner casing 7 comprises a back portion 10 and the sides 11, and fits within the outer casing, as shown. The back of the inner casing at the top and bottom is provided with openings 13, which register with openings of the back of the outer casing, and these openings 14 are designed to receive securing screws, whereby the machine may be fastened to any suitable support.

The inner casing is also provided with struck-up parts 16 forming guides, for the mechanism actuator. The sides of the inner casing near their upper ends are provided with elongated slots 17 through one or the other of which a coin may be deposited, for entering the coin chute.

The coin chute.

Carried by the back of the inner casing are the upper and lower chute casings 18 and 19. The upper chute casing is substantially of the shape shown, having an obliquely disposed flange 20, and the flanges 21 and 22, which engage the back portion of the inner casing. These flanges 20 and 21 are provided with extension lugs 23 and 24, which engage suitable openings 25 of the back of the inner casing, thereby holding the upper chute section in place. The upper chute casing is arranged relatively to the coin slots of the sides of the inner casing, so that when inserting a coin through either of the slots, it will pass between the flanges 20 and 22. In fact, when inserting a coin

through one of the slots; it will roll down the inclined or obliquely disposed flange 20. The upper and lower coin chutes are spaced, and arranged intermediate them is what 5 may be termed a coin gauge 26. This coin gauge 26 engages a depression formed in the back piece of the inner casing, and is especially designed to permit of the passage of a coin therethrough, that is a coin of the proper diameter and thickness. In other 10 words, this coin gauge (which is detailed in a separate figure in the drawings,) comprises a base piece 26^a, which is anchored in the depression of the back piece of the inner casing by means of the lugs 27 and 28, which engage certain openings of the back piece of the inner casing, and a cover plate 26^b, which has side flanges 30, of such proportions as to hold the cover plate so spaced 15 from the base plate, that a coin, preferably a nickel, though not necessarily, may easily and freely pass between the base and cover plates. Furthermore, these flanges are spaced apart, so as to permit a coin of the proper diameter to pass therethrough without binding. This cover plate is slotted arcuately, as shown at 31. The upper portion of the cover plate is flared outwardly as shown at 32, so as to cooperate with the 20 upper coin chute casing, so as to guide the coin into the coin gauge. When a slug too large in diameter passes through this coin gauge, it will tend to bind, and hence will prevent the proper operation of the mechanism. A slug too small in diameter will 25 pass through the coin gauge without affecting an operation of any of the parts of the mechanism. The lower coin chute section comprises a plate 33, which is shaped 30 substantially as shown preferably, though not necessarily, and this plate of the lower coin chute has flanges 34 and 35, which have lugs 36, which are secured in openings 37 of the back piece of the inner casing. The 35 coin gauge which is intermediate the upper and lower coin chute sections, is arranged so as to register with the lower coin chute, so that the coin will properly pass therethrough without binding.

50 The upper and lower coin chute sections are covered by means of the cover plate 38 and the longitudinal edges of this cover plate 38 have notches 39. The opposite sides of the inner casing are provided with inwardly extending lugs 40, and the flanges 41, and the lugs 40 are arranged so as to pass through the notches 39, when the cover plate is inserted. When the cover plate is inserted in the proper position, so that the 55 lugs 40 will pass through the notches, the plate rests upon the inwardly extending flanges 41. The cover plate 38 may then be given a partial movement downwardly, in which case the vertical marginal edges

of the cover plate will engage under the lugs 65 40, thereby locking the cover plate securely in place, and at the same time housing or obscuring the upper and lower and intermediate coin chutes.

Article holding and delivering tray.

A shaft 43 is mounted in suitable bearings on the sides of the inner casing, and supported on this shaft rockably are the ears 44 of an article supporting and delivering tray 45. One of the ears 44 is provided with a plurality of gear teeth 46, which are designed to mesh with the gear openings of the tray actuator. A coil spring is in surrounding relation to the shaft 43, and one of its ends bears against the under surface of the article supporting and delivering tray, to hold the tray in its normal position horizontally. The other end of the coil spring 47 is extended, and is disposed in engagement with the lug 48 of one of the sides of the inner casing, thereby tensioning the spring, to hold the supporting and delivering tray in a horizontal position. The rear edge of the tray is provided with upwardly extending lugs 49, which are designed to engage the rear edge of a pack of chewing gum or other article in such wise that only a single article may be delivered, when the tray is tilted.

95

Coin controlled mechanism for actuating the tray.

The coin controlled mechanism for actuating the tray comprises a rocking lever 50, which is pivotally mounted as at 51 upon a pivot pin 52, adjacent the inner face of the back piece of the inner casing. This rocking lever is provided with an extension 53 provided with an arcuate slot 54, through which a headed pin 55 extends, thereby reinforcing and guiding the rocking lever when in action. Secured in any suitable manner to the back of the back piece of the inner casing is a reinforcing plate 56. This reinforcing plate and the back piece of the inner casing are provided with registering slots 57. The rocking lever 50 has an opening 58, from one edge of which a lug 59 laterally extends. This lug 59 extends through the elongated slots 57 of the back piece of the inner casing and the reinforcing plate, and is adapted to support a coin after it passes through the lower chute. The reinforcing plate 56 near its lower part is provided with an opening 60, from one edge of which a lug 61 extends. This lug 61 extends through an opening of the back piece of the inner casing and is positioned eccentrically with relation to the pivot pin of the rocking lever. This lug 61 is also positioned in such wise relatively to the lug 59, as to assist in supporting a coin, preferably a nickel,

100

110

115

120

125

though not necessarily, when the rocking lever, which is obviously coin actuated, is in its normal position. The further the lever 50 is oscillated downwardly, the greater the space between the lug 59 and 61 becomes, and when the rocking lever substantially reaches the limit of its downward movement, the coin is released, and allowed to fall into the coin receptacle 62. The lug 63 constitutes a guard for the coin actuated lever, so that in case the coin is caught by the starting pawl before it reaches its position between 61 and 59, the mechanism will be guarded and can not move. Were it not for the guard 63 in the form of a lug, it would be possible to catch the coin between the starting pawl and the upper extension of the coin actuated pawl and move the mechanism so that it would wedge and not operate.

Also mounted upon the pivot pin 52 is the starting pawl 64 for the coin controlled mechanism. This starting pawl is provided with gear teeth 65, with which the teeth 66 of the actuator 67 mesh. When the actuator is pushed upwardly, the starting pawl is oscillated on its pivot, until its extension lug 68 engages the edge of the coin, which, after it has been deposited in the chute, lodges between the lugs 59 and 61.

The result of moving the starting pawl its fullest extent causes the extension lug 68 to bear upon the edge of the coin, which in turn will operate the coin actuated lever 50, that is oscillate the same on its pivot, against the action of its spring 69. This spring 69 is connected at one end to a lug 70 on the coin actuated lever 50 and has its other end connected to the extremity of the lug 61, acting to hold the coin actuated lever in its normal position. The starting pawl has a lateral lug 71, which also bears upon the coin and is so positioned as to prevent the coin from disengaging from the extension lug 68.

Also, pivotally mounted upon the pivot pin 52 is a tray operating pawl 72, which may be any suitable shape, preferably as shown, though not necessarily, and the arcuate edge of its extension 73 is provided with a plurality of teeth 74. This tray operating pawl is provided with a segment extension 75 having a plurality of spaced openings 76, which are arranged in an arcuate curve, and are designed to be engaged by the teeth 46 of one of the gears of the article supporting and delivering tray, that is, when the tray operating pawl is oscillated. Projecting from the face of the tray operating pawl is a lateral lug 77, which is engaged by the edge portion 78 of the coin actuated lever 50 for a short distance as shown in Figure 24. When the lever 50 is oscillated, as previously stated, the edge 78 engages the lug 77 for a short distance of

the movement of said lever 50, and imparts a movement to the tray operating pawl until the tray operating pawl reaches the position shown in Figure 25, then by means of the shoulder 66^a of the actuator engaging the lug 79 the tray is tilted, which allows a package of gum to be discharged. The lug 79 is carried by the tray operating pawl and extends laterally in the opposite direction to the lug 77, and is disposed in the path of the segment (which carries the teeth 65) of the starting pawl 64. Since the tray operating pawl is limited in its return movement by its lug 77 coming in contact with the edge 78 of the coin actuated lever, and since the lever is limited in its return movement to its normal position by the lug 63 and the pin in the arcuate curved slot of the extension of the lever, the tray operating pawl is held against the further movement on its return movement. Owing to the tray operating pawl being limited in this manner, the starting pawl 64 is limited in its return movement by the lug 79 of the tray operating pawl contacting with the edge 80 of the starting pawl. Obviously, by limiting the starting pawl in its position on its return movement, the actuator is limited on its return movement, since its teeth are meshing with the teeth of the starting pawl. The slot 57 of the reinforcing plate is provided with a lug 81, which protrudes through the back piece of the inner casing, and is designed to cooperate with the coin as the coin actuated lever 50 is oscillated, in order to force the coin toward and keep it in contact with the lug 61.

Pivottally mounted upon a headed pin 82 is a dog 83, which is substantially of the shape shown, and its lower end has a lateral lug 84, and its upper portion is provided with an additional lateral lug 85. The coil spring 86 is connected to the lug 85 and in turn to a lug of the lower coin chute casing. The lug 85 is positioned relatively to the dog 83, so that the coil spring 86 will hold the dog, so that its lateral lug 84 is positioned directly below the center of the pivot pin 82 of the dog. Should the actuator be partially operated, as shown in the drawings, the teeth 74 of the tray operating pawl will ride past the lug 84, so that the lug may engage certain of said teeth 74, thereby holding the tray in a partial operated position. After the tray has started to tilt, from that point on, the tray may be held in various partly tilted positions. The teeth 74 are five in number, designated by the letters *a*, *b*, *c*, *d* and *e*. When the lug 84 of the dog engages the tooth *a*, the tray will be partially tilted, and the coin actuated lever will be allowed to return to a near normal position through the action of the spring 69. The coin actuated lever is limited in its

near normal position by a lug 87, engaging one of the ears of the tray. This lug 87 is carried by the arcuate extension of the coin actuated lever. However, when the lug 84 of the dog 83 engages the tooth *b*, or the tooth *c*, the tray is held in a partial tilted position, but in a further tilted position than when the lug 84 is in engagement with the tooth *a*. However, when the lug 84 engages either one of the teeth *b* or *c* of the tray operating pawl, the coin actuated lever 50 is prevented from returning toward a normal or a near normal position, particularly owing to the fact that the coin has 15 been allowed to pass further between the lugs 59 and 61 of the coin actuated lever and the reinforcing plate. In other words, the coin wedges between these lugs 59 and 61 upon such further movement of the coin 20 actuated lever, and prevents the return of the lever. When the lug 84 of the dog 83 is in the act of disengaging the tooth *c* and is approaching in engagement with the tooth *d* of the tray operating pawl, the coin 25 is released, which permits the coin actuated lever 50 to return to a near normal position as shown clearly in Figure 26.

Slug catching mechanism.

30 The slug catching mechanism comprises a pawl 88, which is mounted upon a headed pin 89, which is carried by the back piece of the inner casing. In fact, the headed pin 89 engages through an elongated slot 90 of 35 the slug catching pawl. Where the back piece of the inner casing is depressed for the reception of the coin gauge, the back piece is provided with an elongated opening 91. The reinforcing plate which is secured 40 in any suitable manner to the back piece of the inner casing is provided on one of its edges with a pair of lugs 92, which engage through the opening 91. The slug catching pawl has an extension 93, and extending 45 laterally from the extension is a pair of lugs 94. One of the lugs 94 engages through the slot in the coin gauge, in order to contact with a slug, should it wedge in said gauge. These lugs 94 move concentric with the 50 curvature of the slot and the curved edge portion 95 of the gauge, that is when the slug catching pawl is oscillated. When the slug catching pawl returns to its normal position, the lugs 94 contact with the lugs 55 92, so as to limit the slug catching pawl in its normal position.

An actuator return pawl 96 is also pivotally mounted upon the headed pin 89. This actuator return pawl has an extension 60 97, the end portion 98 of which is engaged by a shoulder 99 of an arch portion 100 of the actuator, so that when the actuator is pushed upwardly, the return pawl will be oscillated on its pivot against the action

of its spring 101, the spring acting to return the actuator and the return pawl to their normal positions. This spring has one end connected to a lug 102 of the extension 97 of the return pawl and has its other end connected to a lug 103 of the 70 reinforcing plate. This lug 103 of the reinforcing plate extends through an opening of the back piece of the inner casing. A coil spring 104 is connected at 105 to an extension of the slug catching pawl and has its 75 other end connected to a lug 106 of the reinforcing plate. This lug 106 also extends through the opening in the back piece of the inner casing. The spring 104 acts to return the slug catching pawl to its normal 80 position. The slug catching pawl oscillates at the same time that the actuator return pawl is oscillated. However, the spring 104 exerts an opposite force, which is overcome by the heavier spring 101, tending to return 85 the actuator to its normal position.

An extension of the slug catching pawl has a shoulder 107, which is engaged by a lateral lug 108 of the actuator return pawl. This shoulder 107 is angular, and not only 90 causes the two pawls 88 and 96 to move together, but also holds the slug catching pawl in its raised position, in other words, in a position so that the lower end of the slot 90 of the catching pawl is in engagement with 95 the shank of the headed pin 89. As long as the slug catching pawl is in such a position, and a proper size of coin is allowed to fall through the coin chute, the catching pawl will properly operate. However, should a 100 slug be allowed to pass through the chute and become lodged in the coin gauge, owing to its irregular shape, the slug catching pawl will contact therewith and be prevented from oscillating with the actuator 105 return pawl. The lateral lug 108 of said return pawl will then disengage the shoulder 107, and through the medium of the spring 104, the slug catching pawl will be moved 110 downwardly, until the upper end of the slot 110 89 of said slug catching pawl will engage the shank of the headed pin 89. By this mechanism, the slug is prevented from moving downwardly through the chute, not only 115 because it is held by the extension of the catching pawl, but also because it is wedged in the coin gauge, therefore the operating mechanism for actuating the tray will not operate.

Moreover, the return pawl will not be allowed to return to its full normal position 120 through the action of its spring 101. This is due to the fact that the catching pawl has been lowered, and when the return pawl is in the act of returning to its initial position, 125 its lateral lug 108 will engage the notch 109 of the catching pawl. The return pawl will not only be prevented from returning to a

normal position, but also the catching pawl will be prevented from reaching its initial position.

Actuating mechanism.

The actuating mechanism for the vending machine comprises the actuator 67, which is in the form of an elongated plate or bar. The back piece of the inner casing 10 is provided with struck-up guides 16, while one of the side flanges of the inner casing is provided with said inwardly extending flanges 41, acting as additional guides for the actuator. The lower part of the actuator 15 has a push rod 112 provided with a push button 113, to be engaged by the hand of an operator. Obviously, by an upward movement of the actuator owing to upward pressure on the push button, the coin controlled 20 mechanism will be operated, which will in turn operate the article supporting and discharging tray. The actuator will also operate the slug catching pawl, and also the return pawl. The upper portion of the actuator 25 has a lateral arm 114, which is positioned transversely of the upper coin chute casing. One end of this arm has a lateral lug 115. The upper end of the actuator on its side edge, and in a position opposite the 30 lug 115 is provided with an additional lug 116. These lugs 115 and 116, when the actuator is moved upwardly, overlie the coin receiving slots, thereby preventing a second coin from entering the coin chute. When 35 the lug 84 of the dog 83 engages either one of the teeth *b*, *c* and *d* of the tray operating pawl, the actuator is prevented from returning to its initial position, and the lugs 115 and 116 are held in positions to cover the 40 coin receiving slot. This is due to the fact that the tray operating pawl is prevented from returning to its initial position by the dog 83, while the starting pawl is prevented from returning to its initial position by its 45 edge 80 contacting with the lug 79 of the tray operating pawl, and since the starting pawl is in mesh with the actuator, it is obvious that the actuator is prevented from returning to its initial position.

The top of the outer casing is provided 50 with the usual locking mechanism, which is similar to that illustrated in the heretofore mentioned Patent No. 1,278,186, and this locking mechanism for the cover includes the lever 117, which is pivotally mounted upon the pivot rod of the tray, and has a lateral lug 118 to cooperate with the lock of the cover of the outer casing. This 55 lock 119 of the cover, together with the projecting lug 120 of a strap carried by the cover, holds the cover in a locked position, so that the lock is inaccessible from the exterior. The locking bolt of the lock, and the lug of the strap engage opposite open-

ings 121 of the side flanges of the inner casing. The lower end of the lever 117 has a lateral lug 122, to engage a notch 123 in one of the end walls of the coin receptacle, thereby locking the coin receptacle or box in position, and rendering the same inaccessible from the exterior.

The casing of this vending machine is constructed and put together in a general and similar manner to that set forth and claimed and illustrated in the said copending application, therefore it is unessential to further illustrate the mode of construction of the casing.

In addition to the coin actuated lever being limited in its near normal position by 80 the lug 87, the latter is also designed to fit or engage under one of the ears of the delivering tray when all the parts are in normal positions, so that the tray will be locked against idle movement when all the parts are 85 normal. For instance, were it not for the lug 87, the turning of the tray could be accomplished by the downward pull of an inserted wire on the tray, without inserting a coin. This feature of the invention affords 90 to protect the machine against fraudulent manipulation. In the operation of the machine the edge 78 of the lever 50 cooperates with and pushes upon the lug 77 moving the tray operating pawl 72 and tilting the tray 95 until the lug 84 of the dog 83 is approaching engagement with the tooth *b*. In fact just before the lug 84 of the dog 83 is about to engage the tooth *b*, the edge 78 of the lever 50 ceases to push upon the lug 77, hence the 100 tray is no longer operated by the coin actuated lever 50. In other words after the lug 84 engages with the tooth *b*, the coin actuated lever 50 no longer functions with the lug 77, though a casual examination may 105 lead to the impression that it does. A further tilting movement of the tray is accomplished through the medium of the lug 79 having been moved in the path of the shoulder 66^a and upon further upward movement, 110 said shoulder 66^a bears upon the lug 79, hence completing the delivery movement of the tray. This cooperation between the shoulder 66^a and the lug 79 continues until the article is delivered, as will be seen in 115 Figures 25, 26 and 27. In Figure 27 the shoulder 66^a is still in engagement with the lug 79, and it is to be remembered that pressure is still applied to the actuator. However, as soon as pressure is relieved on the 120 actuator allowing it to return to a normal position, the tray actuating pawl returns to a normal position. When the lug 84 of the dog 83 reaches and engages the tooth *d* as in Figure 26, the coin is released, which allows the coin actuated lever 50 to return to a near normal position, which is disclosed in Figure 26. The shoulder 66^a is obviously 125

still engaging the lug 79, and when the actuator is allowed to return to a normal position, the article having been released or delivered and the coin released, the tray is returned to its initial position. When a coin is deposited in a machine and it becomes positioned as in Figure 22 the edge 78 bears upon the lug 77, and will actuate the tray operating pawl, until the lug 84 of the dog 83 engages the second tooth *b*. In fact the edge 78 would be in engagement with the lug 77 in Figure 23, if pressure upon the actuator is maintained. However it is to be supposed that pressure upon the actuator has been relieved in Figure 23, in order to show that when such pressure is relieved, the coin actuated lever 50 may return to a near normal position, which will permit the edge 78 to disengage from the lug 77, the dog 83 holding the tray tilted. When pressure is resumed on the actuator, the edge 78 is again brought in contact with the lug 77, and the engagement is maintained until the lug 84 is about to engage the tooth *b*, then the engagement ceases as previously stated.

When a coin is released, the coin actuated pawl drops out of position, returning to near normal position by spring action. However, during its forward movement, the edge 78 of the coin actuated lever has forced the tray operating pawl through the medium of the lug 77, so that the tray operating lever at the teeth *a* or *b* of the plurality of teeth 74 has become engaged by the dog 84, locking the tray operating pawl against backward movement. Since the coin operated pawl has now dropped completely out in so far as the functioning in the further operation, further movement of the tray operating pawl is caused by a shoulder 66 of the actuator 67 contacting with the lug 79 of the tray operating pawl, and forcing the complete oscillation of the pawl, thereby causing the release of the dog 84, the release of which allows the entire mechanism to return to normal position.

Should a coin or slug of irregular shape become hung or will not release from the coin actuated pawl at its extreme forward stroke, the coin actuated pawl will be forced and held to its limit or extreme forward stroke, and the corner of the edge 78 will be forced under the partial straight or square edge of the ear 44 of the delivery tray, thereby preventing the delivery tray from making its complete tilting and downward movement. This in turn prevents the tray operating pawl from making its complete movement, and as the dog 84 has engaged the tooth *a* or *b* of the teeth 74 of the arcuate edge of the extension 73 of the tray operating pawl, it is impossible for the mechanism to return to normal position, as it is completely locked both against forward and backward movement.

The invention having been set forth, what is claimed as new and useful is:

1. In an article vending machine, the combination with a casing having an article holding compartment, of an article supporting and delivering tray mounted in the lower part of said compartment, an actuator, a coin controlled mechanism mounted in the casing and operated by the actuator for tilting said tray, said coin controlled mechanism comprising a spring tensioned coin actuated lever, a starting device geared to the actuator and between which and the coin actuated lever, a coin is adapted to engage, and means for limiting the coin actuated lever to a near normal position.

2. In an article vending machine, the combination with a casing having an article holding compartment, of an article supporting and delivering tray mounted in the lower part of said compartment, an actuator, a coin controlled mechanism mounted in the casing and operated by the actuator for tilting said tray, said tray and the coin controlled mechanism having cooperating means for limiting said coin operated mechanism to a near normal position, when the tray is partially tilted.

3. In an article vending machine, the combination with a casing having an article holding compartment, of an article supporting and delivering tray mounted in the lower part of said compartment, an actuator, a coin controlled mechanism mounted in the casing and operated by the actuator for tilting said tray, said coin controlled mechanism comprising a spring tensioned coin actuated lever, a starting device geared to the actuator and between which and the coin actuated lever, a coin is adapted to engage, and cooperative connections between the tray and the lever of said coin controlled mechanism for limiting the coin controlled lever to a near normal position, while the tray is tilted.

4. In an article vending machine, a casing having an article receiving compartment, an article supporting and delivering tray operatively mounted in said compartment, an actuator, a coin controlled mechanism in geared connection with the actuator, a tray tilting device cooperatively connecting with the coin controlled mechanism which is operated by the actuator, whereby as the actuator is reciprocated the tray is tilted, thereby delivering an article, and means carried by the tray and operatively engaging with a member of the coin controlled mechanism to limit said member in a near normal position.

5. In an article vending machine, the combination with a casing having an article receiving compartment, of an article supporting and delivering tray pivotally mounted in the lower part of said compartment, an actuator,

a coin controlled mechanism in geared connection with the actuator, a tray tilting device cooperatively connecting with the coin controlled mechanism which is operated by the

5 actuator, whereby as the actuator is reciprocated the tray is tilted, thereby delivering an article, and means for limiting the coin controlled mechanism to a near normal position while the tray is partially tilted.

10 6. In an article vending machine, the combination with a casing having an article receiving compartment, of an article supporting and delivering tray pivotally mounted in the lower part of said compartment, an

15 actuator, a coin controlled mechanism in geared connection with the actuator, a tray tilting device cooperatively connecting with the coin controlled mechanism which is operated by the actuator, whereby as the actuator

20 is reciprocated the tray is tilted, thereby delivering an article, said coin controlled mechanism including means cooperating with the coin for preventing the coin controlled mechanism from returning to a near normal position, while the tray is partially tilted.

25 7. In an article vending machine, the combination with a casing having an article receiving compartment, of an article sup-

30 porting and delivering tray pivotally mounted in the lower part of said compartment, an actuator, a coin controlled mechanism in geared connection with the actuator, a tray tilting device cooperatively connecting with

35 the coin controlled mechanism which is operated by the actuator, whereby as the actuator is reciprocated the tray is tilted, thereby delivering an article, and means for limiting the coin controlled mechanism to a

40 near normal position while the tray is partially tilted, said casing including a coin chute having coin receiving slots, and means carried by the actuator for covering said slots, thereby preventing a second coin from being inserted in the chute, when the tray is partially tilted.

45 8. In an article vending machine the combination with a casing having an article receiving compartment, of an article sup-

50 porting and delivering tray pivotally mounted in the lower part of said compartment, an actuator, a coin controlled mechanism in geared connection with the actuator, a tray tilting device cooperatively connect-

55 ing with the coin controlled mechanism which is operated by the actuator whereby as the actuator is reciprocated the tray is tilted, thereby delivering an article, said coin controlled mechanism including means

60 cooperating with the coin for preventing the coin controlled mechanism from returning to a near normal position, while the tray is partially tilted, said casing including a coin chute having coin receiving slots, and means

carried by the actuator for covering said 65 slots, thereby preventing a second coin from being inserted in the chute, when the tray is partially tilted.

6. In an article vending machine, the combination with a casing having an article receiving compartment, of an article sup-

70 porting and delivering tray pivotally mounted in the lower part of said compartment, an actuator, a coin controlled mechanism in geared connection with the actuator, 75

a tray tilting device cooperatively connected with the coin controlled mechanism which is operated by the actuator, whereby as the actuator is reciprocated the tray is tilted, thereby delivering an article, said coin con-

80 trolled mechanism including a coin actuated spring tensioned lever provided with an arcuate extension, said tray having an ear, and means carried by the arcuate extension to cooperate with the ear to limit the coin 85 actuated lever in a near normal position.

7. In an article vending machine, the combination with a casing having an article receiving compartment, of an article sup-

90 porting and delivering tray pivotally mounted in the lower part of said compartment, an actuator, a coin controlled mechanism in geared connection with the actuator, 95

a tray tilting device cooperatively connect-

100 ing with the coin controlled mechanism which is operated by the actuator, whereby as the actuator is reciprocated, the tray is tilted, thereby delivering an article, said coin controlled mechanism including a coin actuated spring tensioned lever provided with an arcuate extension, said tray having

105 an ear, means carried by the arcuate extension to cooperate with the ear to limit the coin actuated lever in a near normal position, a starting pawl, and said cooperative 110 connection between the tray and the starting pawl, and the coin controlled lever having means to limit the actuator in a par-

115 tially reciprocated position.

8. In an article vending machine the combination with a casing having an article receiving compartment, of an article sup-

115 porting and delivering tray pivotally mounted in the lower part of said compartment, an actuator, a coin controlled mechanism in geared connection with the actuator, 120

a tray tilting device cooperatively connect-

125 ing with the coin controlled mechanism which is operated by the actuator, whereby as the actuator is reciprocated the tray is tilted, thereby delivering an article, said coin controlled mechanism including a coin actuated spring tensioned lever provided with an arcuate extension, said tray having an ear, means carried by the arcuate extension to cooperate with the ear to limit the coin actuated lever in a near normal position, a starting pawl, and said cooperative

connection between the tray and the starting pawl, and the coin controlled lever having means to limit the actuator in a partially operated position, said casing having a coin receiving chute provided with coin entrance slots, and means carried by the upper end of the actuator to cover said slots.

12. In an article vending machine, the combination with a casing having an article receiving compartment, of an article discharging mechanism mounted in the lower part of the compartment, an oscillatory operator for said mechanism, a coin controlled mechanism including a coin actuated spring tensioned lever, a starting device cooperatively connecting the operator and said lever, between which and the lever a coin engages, an actuator for said starting device, and means cooperating with said operator for the article discharging mechanism, for limiting the article discharging mechanism in a partial operated position.

13. In an article vending machine, the combination with a casing having an article receiving compartment, of an article discharging mechanism mounted in the lower part of the compartment, an oscillatory operator for said mechanism, a coin controlled mechanism including a coin actuated spring tensioned lever, a starting device cooperatively connecting the operator and said lever, between which and the lever a coin engages, an actuator for said starting device, and means cooperating with said operator for the article discharging mechanism, for limiting the article discharging mechanism in a partial operated position, means for limiting the lever of the coin controlled mechanism in a near normal position.

14. In an article vending machine, the combination with a casing having an article receiving compartment, of an article discharging mechanism mounted in the lower part of the compartment, an oscillatory operator for said mechanism, a coin controlled mechanism including a coin actuated spring tensioned lever, a starting device cooperatively connecting the operator and said lever, between which and the lever a coin engages, an actuator for said starting device, and means cooperating with said operator for the article discharging mechanism, for limiting the article discharging mechanism in a partial operated position, means for preventing the coin controlled lever from returning to a normal position after the article discharging mechanism has been operated substantially half its movement.

15. In an article vending machine, the combination with a casing having an article receiving compartment, of an article discharging mechanism mounted in the lower part of the compartment, an oscillatory operator for said mechanism, a coin controlled mechanism

including a coin actuated spring tensioned lever, a starting device cooperatively connecting the operator and said lever, between which and the lever a coin engages, an actuator for said starting device, and means cooperating with said operator for the article discharging mechanism, for limiting the article discharging mechanism in a partial operated position, means for limiting the lever of the coin controlled mechanism in a near normal position, and means for preventing the coin actuated lever from returning to a near normal position.

16. In an article vending machine, the combination with a casing having an article receiving compartment, of an article discharging mechanism mounted in the lower part of the compartment, an oscillatory operator for said mechanism, a coin controlled mechanism including a coin actuated spring tensioned lever, a starting device cooperatively connecting the operator and said lever, between which and the lever a coin engages, an actuator for said starting device, and means cooperating with said operator for the article discharging mechanism, for limiting the article discharging mechanism in a partial operated position, said casing including a coin chute having coin receiving slots, and means carried by the actuator for covering said slots, when the actuator has been partially operated.

17. In a machine as set forth, a casing, an article receiving compartment therein, an article delivering tray operatively mounted in said compartment, a coin controlled mechanism including a coin actuated lever, means operatively engaging between the tray and coin actuated lever for performing the dual function of limiting the lever in a near normal position and holding the tray partly tilted when the tray and mechanism are partially operated.

18. In a machine as set forth, a casing, an article supporting and receiving tray operatively mounted therein, a coin controlled mechanism, including a coin actuated lever, means for partly tilting the tray and partially operating said mechanism, means operatively engaging between the lever and the tray for holding the tray partly tilted and limiting the lever in a near normal position.

19. In a machine as set forth, a casing, an article supporting and receiving tray operatively mounted therein, a coin controlled mechanism including a coin actuated lever, means for partly tilting the tray and partially operating said mechanism, means operatively engaging between the lever and the tray for holding the tray partly tilted and limiting the lever in a near normal position, said mechanism including means dependent upon the position of the coin in said mechanism for preventing the return of the lever to a near normal position.

20. In an article vending machine, an article delivering tilting tray, a coin actuated mechanism for imparting an initial tilting movement to the tray, and means for completing the movements of the tray for delivering the article.
21. In an article vending machine, an article delivering tilting tray, a coin actuated mechanism for imparting initial tilting movement to the tray, the construction and arrangement of the coin actuated mechanism being such as to cease tilting the tray, and means including an actuator for actuating the coin controlled lever and complete the tilting movement of the tray.
22. In an article vending machine, a delivering tilting tray, a coin controlled mechanism for imparting an initial tilting movement to the tray, means for actuating the coin controlled mechanism and completing the tilting movement of the tray, the construction and arrangement of the coin controlled mechanism being such that when the actuator is brought into play to complete the tilting movement of the tray, the coin controlled mechanism ceases to impart tilting movement to the tray.
23. In an article vending machine, a delivering tilting tray, a coin controlled mechanism for imparting an initial tilting movement to the tray, means for actuating the coin controlled mechanism and completing the tilting movement of the tray, the construction and arrangement of the coin controlled mechanism being such that when the actuator is brought into play to complete the tilting movement of the tray, the coin controlled mechanism ceases to impart tilting movement to the tray, and means for progressively checking the movement of the tray during its tilting movement at any time when pressure is relieved on the actuator.
24. In an article vending machine, a delivering tray, a coin controlled mechanism for imparting initial movement to the tray, means including an actuator for completing the movement of the tray, means including a tray operating pawl and detent dog for intermittently checking the tray in different progressive tilting positions whenever pressure is relieved on the actuator.
25. In an article vending machine, a delivering tilting tray, a coin controlled mechanism for imparting initial movement to the tray, means including an actuator for completing the movement of the tray, means including a tray operating pawl and detent dog for intermittently checking the tray in different progressive tilting positions whenever pressure is relieved on the actuator, the construction and arrangement of the coin controlled mechanism being such that when the actuator is brought into play,
- 5 said coin controlled mechanism ceases to impart movement to the tray.
26. In an article vending machine, a delivering tilting tray, a coin controlled mechanism for imparting an initial tilting movement to the tray, means for checking the tray in a tilted position at the time the coin controlled mechanism ceases to impart an initial movement to the tray, and means including an actuator for completing the movement of the delivery tray.
27. In an article vending machine, a delivering tilting tray, a coin controlled mechanism for imparting an initial tilting movement to the tray, means for checking the tray in a tilted position at the time the coin controlled mechanism ceases to impart an initial movement to the tray, and means including an actuator for completing the movement of the delivery tray, the construction and arrangement of the coin controlled mechanism being such that when the tray is checked in a tilted position, the coin controlled mechanism ceases to tilt the tray, whereby the actuator may complete the full tilting movement of the tray.
28. In an article vending machine, a delivering tilting tray, a coin controlled mechanism for imparting an initial tilting movement to the tray, means including a reciprocating actuator for actuating the coin controlled mechanism, thereby completing the tilting movement of the tray, the construction and arrangement of the coin controlled mechanism being such that when the actuator of said means is brought into play to complete the tilting movement of the tray, the coin controlled mechanism ceases to impart tilting movement to the tray.
29. In an article vending machine, a delivering tilting tray, a coin controlled mechanism for imparting an initial tilting movement to the tray, means including a reciprocating actuator for actuating the coin controlled mechanism, thereby completing the tilting movement of the tray, the construction and arrangement of the coin controlled mechanism being such that when the actuator of said means is brought into play to complete the tilting movement of the tray, the coin controlled mechanism ceases to impart tilting movement to the tray, and the tray to a partial tilted position.
30. In an article vending machine, a delivering tilting tray, a coin controlled mechanism for imparting an initial tilting movement to the tray, means including a reciprocating actuator for actuating the coin controlled mechanism, thereby completing the tilting movement of the tray, the construction and arrangement of the coin controlled mechanism being such that when the actuator

ator of said means is brought into play to complete the tilting movement of the tray, the coin controlled mechanism ceases to impart tilting movement to the tray, means co-
operative with a member of the coin con-
trolled mechanism and a part of the tray,
for limiting the coin controlled mechanism

to a near normal position, and retaining the tray in an approximately full tilted position.

In testimony whereof I hereunto affix my signature.

JAMES H. MANN, JR.
